UNITED STATES PATENT OFFICE.

JAMES FAX, OF TORONTO, CANADA.

DESIGN FOR A GAME-BOARD.

SPECIFICATION forming part of Design No. 28,388, dated March 15, 1898.

Application filed August 19, 1897. Serial No. 648,834. Term of patent 14 years.

To all whom it may concern:

Be it known that I, JAMES FAX, a subject of the Queen of Great Britain, residing in Toronto, in the county of York and Province of Ontario, Canada, have invented a new and original Design for a Game-Board, of which the following is a specification, reference being had to the accompanying drawing, which illustrates the game-board.

- o The leading feature of the design is the arrangement of the principal divisions of the game-board and their relation to each other.

A represents the game-board. At each corner of the game-board A is a principal division B, consisting of twenty-four subdivisions b b' , respectively, alternately arranged. The middle subdivision b' of each of the principal divisions B is provided with one or more circles C. At each end of the game-board A is a principal division D, consisting of concentric circles and scrollwork, each principal division D being in the middle of the adjacent principal division B. Adjoining the principal divisions B and D at each end of the board is a principal division E. Each of the principal divisions E consists of fifty-eight subdivisions e e' , respectively, alternately arranged. Interposed between the principal divisions E is a principal division F, consisting of four minor divisions G G' and G'' . The minor division G is located in the

middle of the principal division F and consists of a center H of one or more circles. Surrounding the center H are four subdivisions h , diametrically arranged, and interposed between each adjacent pair of subdivisions h is a subdivision h' . Surrounding the minor division G is a minor division G' , consisting of sixty subdivisions g g' , alternately arranged. The subdivisions g g' are alternately arranged and so disposed that one subdivision g' is located at each corner of the minor division G' , and in each of the corner subdivisions g' is one or more circles, while in the remaining subdivisions g' is the outline of two squares, one arranged within the other. The minor divisions G'' are located one at each side of the principal division F and partly within the minor division G' . Each side of the principal division F is provided with an ornamental scroll, which forms part of the outline of the two divisions I I, and in each of the divisions I I are two flags.

What I claim is—

The design for a game-board, herein shown and described.

Toronto, August 9, A. D. 1897.

JAMES FAX.
